Des. 1802

Samuel H. Ransom, of Albany, N.Y.
Letters Patent No. 1802. Dated July 1st, 1863.

The schedule referred to in these Letters Patent and making part of the same.

To whom it may concern:

Be it known, that I, Samuel H. Ransom, of the City and County of Albany, and State of New York, have produced a new and original design for the Plates of a Cook Stove, which stove is named the "Consul;" and I declare that the annexed delineations are full and accurate representations of the ornamental design on the different plates;—those plates not shown are of the same design as those annexed.

A represents the side of the stove, with its doors.

B   "   the back of the stove:

C   "   the front of the stove, with one of the front doors in:

These with other plates similarly ornamented, when mounted together, forming the cook stove called the "Consul".

What I claim as my production, and desire to secure by Letters Patent, is, the combination and arrangement of ornamental figures and forms represented in the accompanying photographs, forming together the ornamental design for a Cook Stove.
